G. W. STORCH

CARBURETOR

Filed May 17, 1924

Fig. 1.

UNITED STATES PATENT OFFICE.

GEORGE W. STORCH, OF APPLETON, WISCONSIN.

CARBURETOR.

Application filed May 17, 1924. Serial No. 714,009.

To all whom it may concern:

Be it known that I, GEORGE W. STORCH, a citizen of the United States, and resident of Appleton, in the county of Outagamie and 5 State of Wisconsin, have invented certain new and useful Improvements in Carburetors; and I do hereby declare that the following is a full, clear, and exact description thereof.

10 This invention relates to carburetors.

In carburetors as heretofore constructed means have been provided for constricting the flow of air about the nozzle when the engine is running at low speed so as to 15 maintain the requisite suction upon the nozzle. These means, however, have been found defective as they frequently stick at either their upper or lower limits of travel and quickly produce a jerky and unreliable operation.

20 This invention is designed to overcome the above noted defects, and objects of such invention are to provide a carburetor in which means are provided for automatically 25 constricting the air passage adjacent the nozzle when the engine is running at low speed and to so construct this constricting means and associate it with the other portions of the carburetor that sticking is wholly avoided either at the upper or lower limit 30 of travel of the constricting means.

Further objects are to provide a simple 35 type of carburetor in which an apertured disk is employed to automatically constrict the flow of air under predetermined conditions and is so formed that it may be positioned within the carburetor with either 40 face uppermost and will work with equal ease in either position without any danger of sticking.

A further object is to generally simplify and improve the construction of carburetors.

An embodiment of the invention is shown 45 in the accompanying drawings, in which:— Figure 1 is a vertical sectional view through the carburetor showing the disk in its lowermost position.

Figure 2 is a plan view of the disk removed from the remaining portion of the 50 carburetor.

Figure 3 is a sectional view on the line 3—3 of Figure 1.

The carburetor comprises a lower section 55 1 and an upper section 2. This lower section is provided with an air inlet passage 2' and the upper section is provided with

a mixture outlet or delivery passage 3. A float chamber 4 is formed in the lower section and a light float 5 is pivotally mounted, as indicated at 6, to the upper section 2. 60 This float controls the fuel valve 7 which controls the flow of fuel from the fuel inlet 8 into the float chamber.

The lower section 1 is provided with a vertical air passage 9 preferably of cylindrical contour within which an upwardly extending nozzle 10 is centrally mounted. This nozzle communicates by means of a passage or neck 11 with the float chamber and is controlled by a needle valve 12 whose 70 stem 13 projects through a suitable packing in the upper chamber and is provided with a manipulating handle.

It is to be noted that the upper casing or section 2 is provided with a downturned 75 flange 14, and it is further to be noted that the nozzle 10 is provided with an outwardly projecting circular ledge 15 spaced downwardly from the flange 14, as shown in Figure 1. A butterfly control valve 16 is 80 mounted in the outlet 3 and a butterfly choke valve 17 is mounted in the inlet 2. It is to be noted from Figure 1 that the two sections are held together by means of screws 18 and that a small flanged portion 19 is provided 85 in the upper section which fits within the float chamber 4 and accurately centers the parts. However, this centering is also secured by the cooperation of the flange 14 of the upper section with the wall 20 of the air 90 passage 9.

The means for automatically controlling the flow of air and constricting the air passage when the engine is running slowly, may comprise a disk indicated generally at 95 21. This disk is provided with an apertured hub portion 22 provided with upper and lower bosses 23. It is provided with an annular marginal portion 24. This marginal portion is provided with pins 25 which 100 project above and below the upper and lower surfaces thereof. It is to be noted that the hub 22 is provided with inwardly directed lugs 26 which contact with the cylindrical exterior surface of the nozzle 10, 105 and insures free sliding of the disk upon such nozzle. This disk 21 is provided with a plurality of apertures 27 which are uniformly spaced between the marginal and hub portions of the disk.

110 In operation the disk is raised by the flowing air when the engine is operating un-

der normal or full load conditions and the projecting pins contact with the flange 14 when the disk is in its most elevated position. The pins, however, hold the body of the disk from actual contact with the flange and thus prevent sticking. When, however, the engine is running at slow speed, the disk assumes the low position, as shown in Figure 1, and the boss 23 on the low side rests 10 upon the ledge 15 and prevents the body of the disk from contacting with such ledge, consequently preventing sticking.

In view of the small surfaces in contact with the nozzle, that is to say, the lugs 26, 15 the disk will not stick to the nozzle but will freely slide thereon at all times.

It is to be noted that when the disk is in its lowermost position that the ledge 15 partially closes the apertures 27 and constricts 20 the air passage thus insuring adequate suction upon the nozzle.

It is to be noted that the nozzle projects a distance above the fuel level in the float chamber and consequently the flow automatically 25 ceases when the engine is stopped. Further the nozzle is located in a free space in the air passage and consequently the air will freely sweep by the nozzle and atomize any overflow of gasoline or fuel that may be 30 sucked through the nozzle.

It will be seen that an extremely simple type of carburetor has been provided in which automatic means are employed for controlling the suction exerted upon the nozzle 35 in accordance with the flow of air through the carburetor.

It will be noted also that in the practice of this invention, sticking of the disk is wholly prevented under all conditions of 40 operation.

Although the invention has been described in considerable detail, it is to be understood that the invention may be variously em-

bodied and is, therefore, to be limited only as claimed.

45

I claim:

1. In a carburetor the combination of an air passage, a nozzle therein, a ledge formed upon said nozzle, an apertured disk slidably carried by said nozzle and cooperating with said ledge to partially close the apertures in said disk when said disk is closed to said ledge, the marginal edge of said disk being in close proximity to, and out of contact with, the walls of said passage, said disk 50 having a small boss adapted to contact with said ledge when said disk is in its lowest position, said passage having an inwardly projecting shoulder, and pins carried by said disk and adapted to contact with said shoulder when said disk is in its uppermost position.

55

2. In a carburetor the combination of an air passage, a nozzle therein, said air passage having an upper shoulder, a ledge formed 60 upon said nozzle and spaced from said shoulder, and an apertured disk slidably carried by said nozzle and cooperating with said ledge to partially close the apertures in said disk when said disk is close to said ledge, 65 the marginal edge of said disk being in close proximity to and out of contact with the walls of said passage, said disk having a hub provided with a small boss adjacent its center projecting from each side thereof and 70 having pins adjacent its margin projecting from each side thereof and adapted to contact with said shoulder, said disk having ribs on the inner side of said hub forming the only portion of said disk in contact with 75 said nozzle.

80

In testimony that I claim the foregoing I have hereunto set my hand at Appleton, in the county of Outagamie and State of Wisconsin.

GEORGE W. STORCH.
